Attorney

UNITED STATES PATENT OFFICE

JACOB E. BRUBAKER, OF LANCASTER, PENNSYLVANIA

TOY PISTOL

Application filed February 1, 1932. Serial No. 590,232.

This invention relates to toy pistols of the type adapted to successively detonate or explode caps contained in a roll or reel held supported in the magazine of the pistol.

5 A primary object of the invention is to provide a construction that is simple and easy to manufacture, and having relatively few working parts which facilitates assembly and adds materially to the life of the device

10 in use. Another, and distinctive object of the invention is to provide a spring hammer, that is, a hammer preferably made of a single leaf of spring steel which may be rigidly supported at one end and operated at its free end by the trigger mechanism to cooperate with an anvil for exploding the caps.

15 A further object of the invention is to provide a reliable and positive mechanism for feeding the cap tape which will prevent clogging or jamming of the tape, thus insuring positive as well as rapid firing of the caps.

20 With the above and other objects in view, the invention consists in the novel features of construction, combination and arrangement of parts as will be hereinafter more fully described, illustrated in the accompanying drawings and defined in the appended claims.

25 A preferred and practical embodiment of the invention is shown in the accompanying drawing in which:—

Figure 1 is an elevation of the toy pistol with the cover of the mechanism shifted to one side to illustrate the reel of caps in position.

30 Figure 2 is an enlarged view of one section of the body of the pistol showing the various operating parts.

Figure 3 is a detail perspective view of the spring hammer.

35 Referring to the drawing it will be observed from Figure 1 that the present device includes a body simulating a modern automatic pistol, and according to the customary practice the body includes a pair of mating hollow sections held together by suitable fastenings 1. One of these sections, 2 constitutes a carrier for the operating mechanism while the other section 3 constitutes a cover therefor and carries therewith a movable section

4 which provides a cover for the magazine of the pistol formed in the handle thereof.

Referring to Figure 2, it will be observed that the body is provided with a lug 5 which pivotally supports a combined trigger and cap feeding unit designated generally as 6 and having a trigger portion 7 and the rearwardly extending cap feeding portion 8. The said cap or tape feeding portion is preferably forked as shown in Figure 2 to provide a seat or socket 9 for receiving a tape engaging and feeding spring 10, the arrangement being such that the spring is positively held in the socket by mere insertion therein so that the free end thereof may readily cooperate with the tape T which passes over the tape guiding wall 11. One of the arms of the forked tape feeding portion 8 is of substantially V-shaped formation to provide a débris clearing foot portion 12 which operates in advance of the tape feeding spring 10 to remove or clear away exploded cap débris so that the cap will have free access to the location of the anvil 13 when the hammer 14 is moved backward to the dotted line position, for example, shown in Figure 2. As will be seen from Figure 2 the body is provided with a top lug 12a for preventing excess movement of the trigger mechanism to prevent overfeeding.

40 To insure the proper feeding of the tape containing the caps there is also provided a tape holding member 15. This member is preferably in the form of a leaf spring which is held in position due to its engagement with the abutment 16 and the socket 17 so that its free end may be disposed normally to bear against the tape guiding wall 11 so that in loading the magazine, one end of the tape may be conveniently placed between the wall 18 and the free end 19 of the spring thereby to hold the tape in position for engagement by the tape feeding spring 10. To facilitate the insertion of the tape between the wall 11 and the spring, the front edge of the wall is concaved in the vicinity of the end 18 of the spring 15. In connection with the tape guiding wall 11 it is pointed out that the same is preferably provided with an offset baffle wall 19, the purpose of which is to prevent

improper positioning of the cap carrying tape T. That is to say, the wall 19 is of such length that a child or inexperienced person will readily see that the proper way to position the tape is between the wall 11 and the springs 10 and 18 and not between the end of the wall 19 and the spring hammer 14.

Referring more particularly to the spring hammer shown in detail in Figure 3, it will be observed that the same is offset or bent at its lower end as indicated at 14a while its upper end is provided with a detonating head 14b and one edge thereof is cut away as indicated at 14c to provide a shoulder 14d which will hereinafter be more fully referred to. The end 14a of the spring is held against the abutment portion 20 in the handle of the section 2 while the intermediate portion of the spring bears against the fulcrum abutment 21 on the inner side wall of the handle. This causes the head 14b of the hammer to normally lie against the anvil 13.

The combined trigger and tape feeding means, as well as the means for operating the spring hammer, are tensioned by a single spring. That is to say, the combined trigger and cap feeding means is provided with an offset lug 22, which provides a pivot for the trigger operating arm 23. This arm is provided with a hook 24 which receives a coil spring 25 that is anchored to the lug 26 on the inner wall of the body 2. When the spring 25 is in position, the trigger 7 will be pulled forward and likewise the hammer operating arm 23 will be pulled upwardly so that its upper edge will engage the shoulder 14d of the hammer. The arm 23 is notched to provide a shoulder 27 and the forward end 28 thereof is curved to ride against an abutment 29 on the body. Normally, that is, in the position of parts shown in Figure 2, the shoulder 27 on the arm 23 engages with the shoulder 14d of the hammer. Therefore, it will be apparent that when the trigger 7 is pulled against the tension of the spring 25 the arm 23 will move the hammer backwardly, that is away from the anvil 13.

As the curved edge of the end 28 of the lever 23 rides against the abutment 29, the shoulder 27 on the arm is moved away from the shoulder 14d on the hammer, and, when the proper point of travel has been reached, the shoulder 27 on the arm 23 completely releases the spring hammer 14 so that the head 14b will snap back against the anvil 13. As the tape feeding means positions a cap between the anvil 13 and the head 14b of the hammer spring, the said cap will be exploded when the parts referred to come together.

By way of describing briefly the operation of the device, it may be pointed out that the tape T containing the explosive charges or caps is usually in the form of a reel which is placed on the spindle 30. The tape is then threaded between the end 18 of spring

15 and the wall 11 so that a portion thereof projects above 18 to be engaged by the tape feeding spring 10. As the operator pulls the trigger 7, the spring 10 will advance the tape toward the anvil 13. During the advancing movement, it will, of course, be understood that the hammer 14 is moved away from the anvil due to the fact that the arm 23 which controls the hammer moves simultaneously with the trigger and the tape feeding means. When the trigger 7 has reached its limit of backward movement, the tape T comes to rest with the explosive charge positioned at the anvil and then the spring hammer 14 is released to snap toward the anvil and thus explode the cap. This operation may be repeated very rapidly and for the reasons heretofore set forth will cause rapid and quick firing of the caps.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:

1. In a toy pistol the combination with an anvil, hammer means cooperating therewith, a tape guiding wall, a baffle associated with said wall for preventing incorrect leading of the tape, tape feeding means cooperating with said wall and spring controlled trigger operated means for controlling said tape feeding means and said hammer.

2. In a toy pistol having detonating means, the combination of said means with tape feeding means, said tape feeding means comprising a pivoted member having a trigger portion and an offset forked portion providing a socket, a tape guiding wall, a tape feeding spring fitted in said socket and cooperating with said wall, and a débris clearing foot carried by one of the arms of said forked portion and operating in advance of the tape feeding spring.

3. In a toy pistol, cap detonating means, a tape guiding wall, a pivotally supported trigger casting, said casting including a trigger portion and an offset forked portion formed with a spring receiving socket and a débris clearing foot, a spring mounted in said socket and adapted to cooperate with said tape guiding wall to engage and move a tape held between the spring and the wall, an offset pivot lug carried by said casting, a hammer actuating arm mounted on said pivot lug, and a spring anchored at one end to the pistol body and engaging at its other end with said arm to tension the said trigger casting and said hammer actuating arm.

4. A toy pistol including a body simulating

a barrel and a handle, said barrel having an opening lying above the handle, an anvil formed on the body at one end of and at right angles to the plane of said opening in the 5 barrel, a leaf spring hammer anchored at its bottom end in the lower portion of the handle and extending upwardly through the handle whereby its upper end operates in said opening to move toward and from said anvil, said 10 hammer being notched at one edge to provide a shoulder, a tape guiding wall arranged in the handle for directing tape between the free end of the hammer and said anvil, trigger means arranged in the barrel portion 15 of the body and including a pivoted trigger member having means for cooperating with said tape guiding wall to feed tape arranged between said means and the wall when the pivoted trigger is moved, an arm pivoted to 20 the trigger member, said arm having a shoulder adapted to releasably engage the shoulder on the hammer, and a spring anchored at one end to the body and having its other end anchored to the said arm thereby to maintain 25 the latter in engagement with said shouldered portion of the spring hammer and also to tension the pivoted trigger member.

5. A toy pistol including a body simulating a barrel and a handle, said barrel having 30 an opening lying above the handle, an anvil formed within the body at an angle to the axis of the barrel and at one side of the said opening therein, a leaf spring hammer anchored at its bottom end in the lower portion 35 of the handle and extending upwardly through the same whereby its upper end operates in said opening toward and from said anvil, a fulcrum abutment formed within the handle and bearing against the intermediate portion of the leaf spring hammer 40 to tension the lower and upper ends thereof respectively against the anvil and the bottom of the handle, a shoulder formed at one edge of the leaf spring hammer, an abutment 45 within the handle adjacent the lower rear side of said opening, and a notched trigger actuated arm adapted to engage said shoulder on the leaf spring hammer and also adapted to engage said abutment to release 50 engagement between the arm and the hammer.

In testimony whereof I hereunto affix my signature.

JACOB E. BRUBAKER.
